UNITED STATES PATENT OFFICE.

WILLIAM R. NEES, OF LOS ANGELES, CALIFORNIA.

CABINET OR WALL BED.

1,079,658.

Specification of Letters Patent. Patented Nov. 25, 1913.

Application filed July 14, 1913. Serial No. 778,998.

To all whom it may concern:

Be it known that I, WILLIAM R. NEES, a citizen of the United States, residing at the city of Los Angeles, in the county of Los Angeles and State of California, have invented new and useful Improvements in Cabinet or Wall Beds, of which the following is a specification.

My invention relates to that class of wall beds which are adapted to be tilted or turned up into a cabinet or recess in the wall when not required for use and which may be turned down out of the same when required; and the object thereof is to produce a bed which can be easily operated, which is simple in construction and which will avoid any possibility of being accidentally turned up into the recess, and will close the opening in the recess or cabinet when not in use.

Another object is to provide a bed which can be easily operated without the use of weights to counterbalance the same.

I accomplish these objects by the bed described herein and illustrated in the accompanying drawings forming a part hereof in which:

Figure 1 is a side elevation of my improved bed. Fig. 2 is a central vertical section of the same. Fig. 3 is a section on the line 3—3 of Fig. 2.

In the drawings 10 is the casing or cabinet which is provided with an opening 11 in the front thereof and a downwardly swinging panel 12 adapted to close said opening. A rectangular bed frame 13 is slidably mounted upon the upper side of said panel 12 to slide transversely thereof. On the inner ends of the ends of the bed frame are mounted anti-friction rollers 14 which are received in and are adapted to be guided by tracks or guideways 16 U-shaped in cross section secured to the inner sides of the cabinet. These tracks are, in elevation, substantially the shape of a U laid on its side with the open portion extending toward the front of the cabinet and have an enlarged portion 19 in the inner end of the upper leg thereof near the rear wall of the cabinet. A switch cam 20 is pivotally mounted at one end in the enlarged portions of guide ways 16 at a point adjacent the rear wall of the cabinet and has its free end resting upon and registering with the top portion of the inner track so as to form a continuous straight track from the front to the rear of the cabinet for the rollers when the bed is

positioned for use. A pin 21 is rigidly secured to the side of cam 20 and extends outwardly through a slot 22 in the side of the cabinet. A cord 23 has one end secured to pin 21 and then extends upwardly to and over a pulley 24 near the top of the cabinet and then forwardly to and over a pulley 25 near the front of the cabinet and then extends downwardly a short distance and terminates in a tassel or knob as desired. Legs or supports 26 are pivotally secured in slots in the outer end of panel 12 and provide means to support the same when in use.

In operation when it is desired to open the bed for use the operator will pull panel 12 downwardly which will cause the rollers to travel in the guideways and force cam 20 to swing on its pivot upwardly to allow said rollers to pass after which said cam will immediately return to its position. The frame is then drawn outwardly and is ready for use. To close the bed the operator will first grasp cord 23 and pull downwardly. This will cause cam 20 to be elevated. The operator will then push the bed-frame inwardly until it is overbalanced and it will then drop and close the opening. Cam 19 is provided to prevent accidental closing of the bed when it is being used and also provides means whereby the bed may be used without being wholly extended out of the cabinet.

While I have shown my device as applied to a cabinet it will be understood that it is equally applicable to a recess in the wall or like place.

Having described my invention what I claim is:

1. A folding bed comprising a cabinet having an opening in the front thereof; a downwardly swinging closure for said opening; a bed frame slidably mounted upon the upper side of said closure; rollers secured to the outer sides of said bed frame; guideways secured to the inner sides of the cabinet and adapted to guide said rollers when being used.

2. A folding bed comprising a cabinet having an opening in the front thereof; a downwardly swinging closure for said opening; a bed frame slidably mounted upon the upper side of said closure; rollers pivotally secured upon the outer sides of said bed frame; guideways secured to the inner sides of the cabinet adapted to guide said rollers when being used; and means mounted in said

guideways to prevent accidental closure of said cabinet closure.

3. A folding bed comprising a cabinet having an opening in one side thereof; a downwardly swinging closure for said opening; a bed frame in slidable connection with the upper side of said closure; anti-friction rollers mounted on the outer sides of the end of said bed frame at the inner ends thereof; guideways for said rollers secured to the inner sides of the cabinet adapted to guide the inner ends of said bed frame downwardly when desired; means mounted in the guideways to lock the bed frame against downward movement; and means to actuate said last means when desired to close the cabinet.
4. In a folding bed, a cabinet having an opening in one side thereof; a downwardly swinging closure for said cabinet opening;

a bed frame in slidable engagement with the upper side of said closure; anti-friction rollers mounted on the ends of the bed frame; guideways for said rollers mounted within and on the lower ends of the cabinet, 25 said guideways extending rearwardly and then rearwardly and downwardly and then downwardly and forwardly whereby when the bed frame is pushed into the cabinet the inner end descends and the outer end of the 30 bed frame carries the closure of the cabinet into its closing position.

In witness that I claim the foregoing I have hereunto subscribed my name this 5th day of July, 1913.

WILLIAM R. NEES.
